UNITED STATES PATENT OFFICE.

WILLIAM H. GATES, OF NEW HAVEN, CONNECTICUT.

COLLAPSIBLE TAP.

1,209,139.

Specification of Letters Patent. Patented Dec. 19, 1916.

Application filed September 10, 1915. Serial No. 49,896.

To all whom it may concern:

Be it known that I, WILLIAM H. GATES, a citizen of the United States, residing at New Haven, in the county of New Haven and State of Connecticut, have invented certain new and useful Improvements in Collapsible Taps; and I do hereby declare the following to be a full, clear, and exact description of the invention, such as will enable others skilled in the art to which it appertains to make and use the same.

My invention relates to collapsible taps and it consists in certain details of construction to be more fully set forth in the following specification.

Referring to the drawings,

Figure 1 represents a broken view partly in section of the head, its shank, and sliding shell on line 1, 1 of Fig. 3, showing the threading dies in operative position; Fig. 2 is a broken view partly in section of the head, its shank, and sliding shell on line 2, 2 of Fig. 3, showing the threading dies in operative position; Fig. 3 is a front elevation 25 of the tool with the front plate removed; Fig. 4 is a broken sectional view of the sliding shell on line 4 of Fig. 2, showing the trip lever mechanism in its normal closed position; Fig. 5 is a view similar to Fig. 4, but 30 showing the position of the trip lever when the sliding shell is released; Fig. 6 is a detail view of one of the threading dies; Fig. 7 is a detail view of one of the cam bolts; Fig. 8 is a detail view of one of the studs for 35 actuating the cam bolts; Fig. 9 is a broken view partly in section of the tool showing the threading dies collapsed; Fig. 10 is a section on line 10, 10 of Fig. 9; Figs. 11, 12, 13 and 14 are detail views of the sliding shell 40 and locking mechanism.

The body of the tap comprises the end 1 carrying the threading dies 2, 3, 4 and 5, the enlarged portion 6 and the shank 7, which latter is adapted to enter a rotatable turret 45 head—not shown. The dies are mounted to have a radial movement in the slots 8 formed in the forward end 1 of the tap body, and they are held in workable position therein by the plate 9, which plate is held in place 50 by suitable screws, one of which, 10, is shown in Fig. 2. In Fig. 3 are shown the threaded holes 11 for said screws.

The threading bits or dies are actuated to open and close through the medium of the 55 bolts 12, which bolts have a longitudinally reciprocating movement in the holes 13

formed in the body of the tap. On the forward ends of these bolts are formed the cams 14, Fig. 7. Cam grooves—one of which, 15, is clearly shown in Fig. 6—are formed in the cutting face of each die to receive the cam projections of said bolts. The cam bolts are actuated through the medium of the studs 16 anchored in the sliding shell 17 and are additionally secured therein by the pins 18 shown in Figs. 1 and 8. The forward end of each of these studs 16 is provided with the hook portion 19, Fig. 8, adapted to engage the notch 20 in the rear end of each cam bolt as shown in Figs. 1, 9 and 7. In order to 70 employ the same method of actuating dies for internal threading to open and close through the medium of longitudinally operating cam members carried by a sliding shell, as applied to dies for external threading, it was found necessary to employ additional members like, for instance, the studs 16 to actuate the cam members or bolts 12, as said bolts, in order to actuate the dies, must necessarily be located so far within the 80 body of the tap as to render it impossible to connect them directly to the sliding shell. The shell 17 is slidably mounted on the shank 7, and its forward end is recessed to also embrace the enlarged portion 6 of the 85 body of the tap. The mechanism for automatically locking the shell in its advanced position and releasing the same is the same as shown in the patent granted to me on August 3, 1915, No. 1,148,510. A brief description of this mechanism will be necessary to show its connection with the present construction. The locking member 21, Fig. 14, is operatively located in the recess 22, Fig. 2, of the tap body and is outwardly 90 actuated by the spring 23. 24—see also Figs. 12 and 13—is a disk rotatably inserted in the shell 17 and maintained therein by the indicator dial 25—shown also in Fig. 11. The under side of the disk 24 is provided 100 with the cam recess 26 adapted to receive the upper end 27, Fig. 14, of the locking member.

The cam pin 28, Figs. 2, 4 and 5, is journaled in the rear wall of the shell 17 and 105 is embraced by the trip lever 29 and is secured thereto by the pin 30. This lever is located and adapted to operate in the recess 31 of the sliding shell. The reduced portion 32 of the cam pin 28 enters the recess 33 of the locking member 21 so that, when the tool has advanced the proper dis-

tance, a trip—not shown—will engage the projecting end of the trip lever 29 and turn the same into the position shown in Fig. 5. This movement of the trip lever will depress 5 the locking member 21 and carry it out of the cam recess 26 and thus release the sliding shell 17, which is then forced rearward by the springs 34. This return movement of the shell carries with it the studs 18 10 and sliding cam bolts 12, and the return of the cam bolts will draw the threading dies inward and thus release the cutting operation. The turret will then withdraw the tap body from the work. Immediately after 15 the release of the shell, the flat spring 35 will return the trip lever 29 to its normal position shown in Fig. 4. To disengage the dies from the cam bolts and remove them from the tap after the front plate 9 20 is removed, the cut away or relief 36, Fig. 6, is made to enable the dies to draw off freely—in the direction of arrow *a*, Fig. 9—from the cam projection 14 of the bolt 12. As the operative travel of this cam pro- 25 jection is only from *a* to *b*, Fig. 6, it is quite evident that the dies could not be re- moved or entered were the cam slot of uni- form width. The inner end of the stop pin 37, Fig. 2, carried by the shell 17, travels 30 in the groove 38, formed in the shank 7, to limit the outward travel of the shell.

Copies of this patent may be obtained for five cents each, by addressing the "Commissioner of Patents, Washington, D. C."

Having thus described my invention, what I claim is:

1. A tap body, threading dies removably located therein having cam grooves in their faces, sliding bolts having cams to register with the cam grooves of the dies, a sliding shell embracing the tap body, means for locking the same thereto and unlocking it therefrom, and members carried by the shell to engage with said bolts and actuate the same to open and close the threading dies.

2. A tap body, threading dies removably located therein having cam grooves in their faces, longitudinally operating cam members adapted to register with the cam grooves of the dies, said tap body having an enlarged portion and a shank portion, a sliding shell embracing said shank and enlarged part of the tap body, means for locking the same to said enlarged portion of the tap body and unlocking it therefrom, and members carried by the shell to engage with said cam member to actuate them to open and close the threading dies.

In testimony whereof I affix my signature in presence of two witnesses.

WILLIAM H. GATES.
